HAT DYEING DEVICE

John J. G. Ryan, Danbury, Conn.

Application April 28, 1937, Serial No. 139,383

10 Claims. (Cl. 223—10)

This invention relates to new and useful improvements in dyeing apparatus and has particular relation to a hat dyeing device.

An object of the invention is to provide means whereby with a minimum of inexpensive equipment large quantities of hat bodies may be uniformly dyed in an expeditious manner.

Another object is to provide a device in which the hat bodies may be evenly and uniformly dyed after they have been fully shrunk, as dyeing in the fully shrunk state gives better and more uniform color and better quality as the coloring or dye is not lost during shrinking as is the case where the bodies are dyed before shrinking.

15 A further object is to provide a device for dyeing hat bodies which eliminates the necessity of knocking down the hats before placing in the dyeing apparatus and then straightening them again as is necessary in the usual dyeing apparatus.

20 A still further object is to provide a simple and effective device which keeps the individual hat bodies separated from each other in the liquor so as to permit the dyeing liquor access uniformly 25 to all parts of the body and thus eliminate unevenness in dyeing or spotty hats.

Other objects and advantages will become apparent from a consideration of the following detailed description taken in connection with the 30 accompanying drawing wherein a satisfactory embodiment of the invention is shown. However, it is to be understood that the invention is not limited to the details disclosed but includes all such variations and modifications as fall within 35 the spirit of the invention and the scope of the appended claims.

In the drawing:

Fig. 1 is a top plan view of the apparatus of the invention while in use;

40 Fig. 2 is a side view thereof, the near side of the dye tank or vat being removed;

Fig. 3 is a plan view on an enlarged scale showing one of the improved holders or frames employed;

45 Fig. 4 is an edge view at right angles to Fig. 3 and showing hat bodies on the frames;

Fig. 5 is a plan view of a felt hat body to be dyed;

Fig. 6 is an edge view thereof; and

50 Fig. 7 is a view looking into the open end of a hat body.

Referring in detail to the drawing at 10 is shown a vat or tank for dye liquor. The vat is shown as rectangular, and within the lower 55 portion thereof is a perforated pipe 11 through

which air is fed or admitted to the lower portion of the vat whereby to have the air agitate the dye therein and thus cause a relative movement between the dye and hat bodies being dyed, as will later more fully appear.

The hat bodies 9 are to be placed in the vat 10 and removed therefrom in large quantities, and to that end a central post 12 is provided to support a large number of forms or frames 13 each constructed to support a hat body. The frames 10 are all alike and in the form shown each includes a bar 14 to the outer end of which are pivoted side members 15 secured as by a friction pivot 16. To the free ends of the short side members 15 friction pivots 17 secure other side members 18 15 to which are secured additional side members 19.

Members 19 are each provided with a longitudinally extending slot 20 through which bolts 21 attach them to the members 18 whereby on loosening of the bolts 21 the members 19 are adjustable longitudinally of the members 18. On the free ends of members 19 are arms 22 directed inwardly toward the bar and preferably arranged in a plane slightly above that of the bar as shown. By adjusting the members 15 and 18 about the 25 friction pivots 16 and 17 and by adjusting the member 19 longitudinally of the member 18 the holder may be made to properly support different sizes and shapes of hat bodies.

The corners are removed from the central post 30 12 and the inner ends of the bars 14 of the holders or frames 13 are bent to provide attaching means 23 through which screws or other fastening means 24 are passed securing the bars to the flattened corner portions of the post. The holders or 35 frames 13 are arranged in four vertical rows on the post with the members 15, 18 and 19 at the horizontal sides of the bars 14.

A clip 25 is secured in any suitable manner (such for example as welding) to the underside 40 of each bar 14, and it is noted (see Fig. 4) that the free ends of the clips are toward the outer ends of the bars and are spaced a short distance below the bars. Each frame 13 also includes an anchoring or securing means 26 in the form of an 45 arm pivoted at 27 between a pair of ears 28 on the upper side of the bar 14 and on its forward lower side provided with a sharp or pointed lug 29. This lug may be tapered on its outer side so the edge of the hat body may be easily slipped 50 under it as the body is slid onto the holder but the point holds it from sliding off until released.

All hat bodies 9 are of about the same shape as shown in Figs. 5, 6 and 7 and when in a substantially flat condition as in such figures each in- 55

cludes sides 30 and 31 and is open at one end 32. Ordinarily when dyeing hat bodies the crowns of the latter are knocked in and the bodies are thrown into a rotatable perforated drum located 5 in a vat or tank of dye and the drum is rotated to have the dye reach all parts of the bodies. Before being placed in the tank the crowns of the bodies are knocked in so that the bodies will not lie flat against one another to reduce as much as 10 possible uneven or spotted dyeing. After the bodies are dyed they must be straightened again.

According to the present invention a large rotary drum and associated mechanism is not necessary, and the operations of knocking in and straightening of the crown is eliminated. While 15 the post 12 is out of the tank or vat 10 hat bodies are placed on the frames 13. First, of course, the frames are adjusted to the proper size as above explained and then the hat bodies are 20 placed one on each frame 13. This disposes the bodies one above the other in vertical rows and supports them in a substantially flat condition.

The free edge portion of the upper side 30 of 25 the body is in each instance supported by the inwardly directed arms 22 so that such portion of the body is held above the lower side thereof whereby the open end of the body is maintained open for the admission of dye as will appear. Further, the lower side of each body is 30 placed on the clip 25 of its frame so that such side of each body is kept from sagging down against the upper side of the body on the next lowermost frame. In this way the sides of a 35 hat body are kept spaced from one another and from the sides of the next adjacent hat bodies on the frames in the same vertical row. This permits the dye liquor to have access readily and uniformly to all parts of the hat, giving uniform dyeing and eliminating unevenness in dyeing 40 or spotty hats. After a hat body is placed on a frame 13 the securing means 26 of such frame may be swung into place or the edge of body may be slid under this device, and its pointed lug 29 engages the said hat body securing the 45 same against casual movement off the frame.

With the hat bodies assembled on the frames as described, the assembly, including the post 12 and the frames 13, can be placed in the tank or vat 10. To this end a hook or eye 33 is provided 50 on the upper end of the post to be engaged by some lifting means (not shown) whereby the assembly may be lifted into the tank 10. Thereafter the dye in the tank is agitated by the admission of air thereto through the perforated pipe 11. The hat bodies being held open 55 the dye may enter them, and as they are supported against contact with one another the dye may reach all parts of the bodies and they are thoroughly and uniformly dyed. After the dyeing operation the lifting means is again applied to the eye 33 and the assembly removed from the tank whereupon the dye bodies may be easily 60 removed from the frames.

The hat bodies may be fully shrunk before 65 being applied to the frames 13 and a better and more uniform quality of dyeing is therefore obtained, because as the dyeing is done after the shrinking there is no dye to be lost or faded in the shrinking operation. There is a further 70 advantage in dyeing after shrinking in that the bodies shrink faster when the shrinking operation is performed before the bodies are dyed. Usually the fur shrinks slower after dyeing as it is opened in boiling in the dye and so does 75 not shrink as fast.

This device does not require a power drive as in the drum type, and requires much less space in the shop.

It is to be understood the device is not limited to having the side members adjustable, as 5 if only hats of a certain size or about the same size are to be dyed the support may be made in one or more pieces and of the proper size to fit these hat bodies. Also, I am not limited to the flat bars as shown as it may be made of 10 wire or any stock of the desired form. The material should be some material neutral to the 15 dye and also which will not stain the hats. Stainless steel is very satisfactory for this purpose, but other materials having the desired characteristics may also be used.

Having thus set forth the nature of my invention, what I claim is:

1. In a hat dyeing device, a frame for supporting conically shaped hat bodies in a flattened condition in the dyeing material comprising a mounting bar to be inserted in the hat body with its outer end in the tip thereof, a pair of side members pivoted to the outer end of the bar and extending back along the same at 25 opposite horizontal sides thereof in diverging relation and in substantially the same plane to support the sides of the hat body in flattened relation and on opposite sides of the bar, and each of said side members including a pair of 30 parts connected for longitudinal adjustment to support different sizes of bodies.

2. In a hat dyeing device, a frame for supporting conically shaped hat bodies in a flattened condition comprising a mounting bar to be 35 inserted in a body with its free end at the tip of the body, side members attached to the outer end of said bar and extending back along the same in diverging relation on opposite sides of the bar to support the sides of the body with 40 the flattened portions above and below the bar, and arms on the free ends of said members and directed inwardly toward the bar to support the free edge of the upper flattened side of the hat body on the frame.

3. In a hat dyeing device, a frame for supporting a conically shaped hat body in flattened condition in the dyeing material comprising a mounting bar, side members attached to the outer end of said bar and extending back along the sides thereof in diverging relation, said frame being adapted to be inserted in a hat body with the free end of the bar at the tip of the body and the sides of the frame supporting the sides of the body in flattened condition with the flattened sides above and below the bar, and a clip 50 extending longitudinally of said bar at the underside thereof to pass under the lower flattened side of the hat body on the frame and support such side above the hat body on a next lower- 55 most frame.

4. In a hat dyeing device, a frame for supporting conically shaped hat bodies in a flattened condition in the dyeing material comprising a mounting bar, oppositely extending side members pivoted at their adjacent ends to one end of said bar, other side members pivoted to the free ends of the first side members, other members attached to and longitudinally adjustable on the second mentioned side members to vary the lengths thereof 65 for different sizes of bodies, said frame being insertable in the body with the free end of the bar at the tip thereof and the side members supporting the sides of the body with its flattened portions above and below the bar, and arms on 70 75

the free ends of the longitudinally adjustable side members and extending inwardly toward said bar to support the free edge portion of the upper flattened side of the hat body on the frame.

5. In a hat dyeing device, a frame for supporting a conically shaped hat body in a flattened condition in dyeing liquid comprising a mounting bar, oppositely extending side members pivoted at their adjacent ends to one end of the bar, other side members pivoted to the free ends of the first side members, other members attached to and longitudinally adjustable on the second mentioned side members to vary the lengths thereof for different sizes of bodies, said frame being insertable into the body with the free end of the bar at the tip thereof and the side members supporting the body with its flattened portions above and below the bar, arms on the free ends of the longitudinally adjustable members and extending inwardly toward the bar to support the free edge portion of the upper flattened side of the hat body on the frame, and a clip extending longitudinally of said bar at the underside thereof to pass under the lower flattened side of the hat body on one frame and support such side above the hat body on a next lowermost frame.

6. In a hat dyeing device, a frame for supporting a conically shaped hat body in a flattened condition in the dyeing material comprising a mounting bar, oppositely extending side members pivoted at their adjacent ends to one end of the bar, other side members pivoted to the free ends of the first side members, other members attached to and longitudinally adjustable on the second mentioned side members to vary the length thereof for different sizes of bodies, said frame being adapted to be inserted in the body with the free end of the bar at the tip of the body and the side members supporting the body with its flattened portions above and below the bar, arms on the free ends of the longitudinally adjustable members and extending inwardly toward the bar to support the free edge portion of the upper flattened side of the hat body on the frame, and means to engage a hat body on the frame and prevent casual movement of such body off the frame.

7. In a hat dyeing device, a central post, a plurality of frames supported on said post and arranged in vertical rows, said frames extending

substantially horizontally from the post and spaced one above the other in the rows, and said frames being so shaped as to support conically shaped hat bodies in flattened condition in horizontal positions in the dyeing material and with the hat bodies on the frames of each row disposed in spaced relation one above the other.

8. In a hat dyeing device, a central post, a plurality of frames supported on the post, said frames being arranged in vertical rows and extending substantially horizontally from the post in spaced relation one above the other in the rows, and said frames being so shaped as to support conically shaped hat bodies in flattened condition in horizontal positions in the dyeing material and with the hat bodies on the frames of each row disposed in spaced relation one above the other, and each of said frames including a portion extending under and supporting the free edge of the upper flattened side of its hat body in spaced relation to the lower flattened side thereof.

9. In a hat dyeing device, a central post, a plurality of frames supported on said post in substantially horizontal position and arranged in spaced relation one above the other in vertical rows, said frames being so shaped as to support conically shaped hat bodies in flattened condition in horizontal positions with the hat bodies on the frames of each row disposed in spaced relation one above the other, and each of said frames including means supporting the lower flattened side of its hat body above the upper flattened side of the hat body on the next lowermost frame.

10. In a hat dyeing device, a central post, a plurality of frames supported on the post in substantially horizontal position and arranged in spaced relation one above the other in vertical rows, said frame being so shaped as to support conically shaped hat bodies in flattened condition in horizontal positions with the hat bodies on the frames of each row disposed in spaced relation one above the other, each of said frames including a portion supporting the free edge of the upper flattened side of its hat body in spaced relation to the lower flattened side thereof, and means on each frame extending under and supporting the lower flattened side of its hat body above the upper flattened side of the hat body on the next lowermost frame.

JOHN J. G. RYAN. 50
